ATTORNEY

UNITED STATES PATENT OFFICE.

SAMUEL J. OLSHIN, OF YONKERS, NEW YORK.

SKYLIGHT OR VENTILATED ROOF.

Application filed August 23, 1920. Serial No. 405,306.

To all whom it may concern:

Be it known that I, SAMUEL J. OLSHIN, a citizen of the United States, residing at 1 Undercliff, Yonkers, in the county of West-
5 chester and State of New York, have invent-
ed certain new and useful Improvements in
Skylights or Ventilated Roofs, of which the
following is a specification.

This invention relates to an automatically
10 operated ventilator. One of the objects of
the invention is to provide a ventilator that
will open automatically in case of fire. An-
other object is to provide a ventilator that
may be opened and closed manually with a
15 minimum of noise. Another object is to
provide a ventilator that is substantially air
tight when in a closed position. Another
object is to provide a ventilator that will
not let rain into the building even when the
20 ventilator is in its open position unless the
rain is accompanied by a considerable
amount of wind. Another object is to pro-
vide a ventilator that will in its closed po-
sition effectively shut out rain even in the
25 most violent storm. Another object is to
provide a ventilator by means of which ade-
quate ventilation can be secured in a prac-
tical and convenient manner. Other objects
and advantages of the invention will be ob-
30 vious as the description proceeds.

The invention will be understood from the
following description and the accompanying
drawings which show an embodiment of
the invention in which the same reference
35 characters refer to the same parts in the dif-
ferent views.

In the drawings:

Fig. 1 is a side view of the device as used
on the side of a peak roof;

40 Fig. 2 is a similar view showing the sashes
in a closed position on the other side of the
peak roof;

Fig. 3 is a plan view;

45 Fig. 4 is a perspective view showing a
sash and operating rods;

Figs. 5 and 6 are views showing details
of the mechanism.

In the drawings reference character 1 re-
fers to the rafters which are shown coming
50 together at the top in a peak roof skylight.
Pivoted between the rafters 1 are series of
window sashes 2, 2', 2, etc., so mounted that
the lower edge of each sash overlaps the
upper edge of the one below it when the

sashes are in a closed position as shown in 55
Fig. 2. The sashes are each provided with a
projecting lip 3 extending along the under
side of their lower edges and with a strip 4
of resilient material such as rubber for ex-
ample extending along the top side of the 60
upper edge thereof. The strips 4 may be
provided with notches 5 so as to fit more
closely the framework or outlines along the
underside of the sashes above with which
they come into contact when they are in a 65
closed position, thereby forming substan-
tially air tight joints between contiguous
sashes.

Extending from each side of the sashes 2,
2', etc. near the point 6 (Fig. 4) at which the
70 sashes are pivoted, are brackets 7 that are
connected by pivots 8 to operating bars,
there being an operating bar 9 along each
side of every series or set of vertical sashes.
Each operating bar 9 is pivotally connected 75
by a link 10 that is also pivotally connected
to an arm 11 which arm 11 is in turn rigidly
connected to the operating rod or shaft 12
which is mounted to turn in bearings 13
mounted upon cross pieces 14 which are se-
80 cured to the rafters 1 at a convenient height.
The arm 15 is adjustably connected by
means of a set screw 16 to the rod 12 in such
a position that the arm 15 comes into contact
with and is stopped in its travel by the op-
85 erating shaft or rod 12' for the sashes on the
opposite side of the peak roof skylight which
is shown in Fig. 2. The operating rod 12'
for its side of the skylight is shown in its
90 actual position in dotted lines in Fig. 1, the
views in the two figures showing the two re-
spective sides of the skylight slightly sepa-
rated from each other, and the sashes being
shown open in one view and closed in the
other view. It is obvious that by adjusting 95
the position of the arm 15 on rod 12 by
means of set screw 16 the extent to which
the sashes can be opened will be determined.
The end of the arm 15 and the end of a cor-
100 responding arm on the rod 12' will be con-
nected to the bifurcated end of a rope 17
which has a fusible link 18 therein.

It is impractical to mount the sashes 2 be-
tween the rafters 1 with a sufficiently close
fit to prevent water from entering between 105
the sides of the sashes and the sides of the
rafters. In fact since it is desirable to have
the sashes 2 to turn readily on their pivots

it is advisable to have a small, free space between the two. This makes it necessary to provide a cover arrangement for these spaces between the rafters and the adjacent sides of 5 the sashes. Such an arrangement is shown consisting of covers 20 and 21 corresponding to or suitable for each pair of side-by-side sashes. These covers 20 and 21 are of substantially the same shape in cross section 10 which shape is clearly shown in Fig. 5. The cover 20 is pivoted at the points 22 to the rafter 1 and its lower end extends a short distance below the point 6 where the corresponding sash is pivoted to the rafter 1. 15 The cover 21 is of substantially the same shape as the cover 20 and is fixedly connected to the adjacent edges of side-by-side sashes in such a manner as to extend horizontally over the spaces between the sashes 20 and rafters 1, thereby forming a continuous sash. The upper end of the cover 21 terminates somewhat below the pivot points 6 so as not to interfere with the opening of the sashes. The cover 20 which is pivoted to 25 the rafter 1 overlaps the upper end of the cover 21 and the cover 21 overlaps the upper end of the next lower pivoted cover 20. The cover 20 may be offset near its upper end as shown at 23 in order to facilitate this overlapping.

The operation is as follows: When it is desired to close the ventilator, tension is applied to the rope 17 whereupon the arms 15 are pulled downwardly and the operating rods 12 and 12' are turned in their bearings thus through the mediation of the arms 11, links 10, and operating bars 9 the sashes are all turned together about their pivot points 6 to their closed position as shown in Fig. 40 2. The resilient strips 4 of the respective sashes come into contact with the lower sides of adjacent sashes that are higher up thus providing a substantially air tight ventilator. When the rope 17 is released or 45 when in case of fire the fusible link 18 is melted the weight of the rods 9 etc. will turn the sashes to their open position as shown in Fig. 1. If necessary the sashes may be so pivoted as to tend normally to 50 turn to their open position by having the pivot points nearer their lower than their upper ends. By proper adjustment of the arm 15 on the rod 12 the sashes can be made to stop at the desired open position with 55 the arm 15 in contact with the lower side of rod 12'. Preferably, this adjustment will be so made that when the sashes are in their extreme open position they will slope downwardly slightly thus taking care of ordinary rain that does not descend at too great a slant. When the sashes are being turned about their pivots 6 towards their open position the covers 21 are carried upwardly and the covers 20 are turned about their 60 pivots 22, their lower ends sliding along the

tops of the covers 21 to the positions shown in Fig. 1.

While the invention has been described as applied to a peak roof ventilator it is obvious that it is also applicable to a ventilator 70 that has only one sloping side. It is also obvious that since the usual building regulations permit the total area of glass to be as small as the area of the opening through the roof, a portion of the glass can be left off 75 and sheet iron or other material substituted therefor. This modification does not violate the requirement that the total ventilating space when the sashes are open shall equal the opening through the roof. 80

I claim:

1. In a device of the class described, a pivoted window sash and means for automatically turning said sash to a predetermined position, said means comprising a 85 rotatable rod and an adjustable arm on said rod.

2. In a device of the class described, a series of pivoted sashes, said sashes being connected by means of brackets on the sides 90 thereof to operating bars, said bars being connected to an operating shaft which extends transverse said sashes, and cover plates extending over the edges of said sashes. 95

3. In a device of the class described, a series of pivoted sashes, said sashes being connected by means of brackets on the sides thereof to operating bars, said bars being connected to a transversely extending operating shaft in such a manner that said sashes tend to turn by their own weight to their open position, said brackets and bars being located entirely on one side of said sashes. 100

4. In a device of the class described, a 105 series of pivoted sashes, said sashes being connected by means of brackets on the sides thereof to operating bars, said bars being connected to an operating shaft in such a manner that said sashes tend to turn by 110 their own weight to their open position, said brackets and bars being located entirely on one side of said sashes, and means adjustable to predetermine the extent of opening of said sashes. 115

5. In a device of the class described, a window sash having a bracket arm extending therefrom and having a strip of resilient material extending thereacross, said strip being notched to fit closely a preceding sash. 120

6. In a device of the class described, two window sashes pivoted on opposite sides of a rafter, a cover fixed to the lower portion of said sashes, and a pivoted cover extending over the upper portion of said sashes. 125

7. In a device of the class described, two window sashes pivoted on opposite sides of a rafter, a cover fixed to the lower portion of said sashes, a pivoted cover extending over the upper portion of said sashes, grav- 130

- ity operated means for opening said sashes, and means to predetermine the extent of opening said sashes.
8. In a device of the class described, two window sashes pivoted on opposite sides of a rafter, and means connected to said sashes to cover a portion of said rafter and means pivoted to said rafter to cover the remainder thereof.
- 10 9. In a device of the class described, two window sashes pivoted on opposite sides of a rafter, and means connected to said sashes to cover a portion of said rafter and pivoted
- means connected to said rafter and overlapping said first named means to cover another portion of said rafter.
10. In a device of the class described, two window sashes pivoted on opposite sides of a rafter, a cover for a portion of said rafter rigidly connected to said sashes, and a cover for another portion of said rafter pivotally connected to said rafter and overlapping said rigidly connected cover.

In testimony whereof I affix my signature.

SAMUEL J. OLSHIN.
